UNITED STATES PATENT OFFICE.

LOUIS PHILIPPE THERRIAULT, OF BONFIELD, ONTARIO, CANADA.

CAN-OPENER.

No. 874,457.

Specification of Letters Patent.

Patented Dec. 24, 1907.

Application filed August 10, 1907. Serial No. 388,021.

To all whom it may concern:

Be it known that I, LOUIS PHILIPPE THERRIAULT, a subject of the King of Great Britain, residing at Bonfield, in the county of Nipissing, Province of Ontario, Canada, have invented certain new and useful Improvements in Can-Openers; and I do hereby declare that the following is a full, clear, and exact description of the invention, such as will enable others skilled in the art to which it appertains to make and use the same.

My invention relates to can openers; the object of my invention is to provide a can opener which can be folded, and the cutting point of which is protected by a pocket in the handle when it is folded; a further object is to provide an adjustable can opener adapted to open cans of varying sizes; and, my invention consists of the combination, construction and arrangement of parts, as herein illustrated, described and claimed.

In the accompanying drawings, forming part of this application, I have illustrated one form of embodiment of my invention, in which drawings similar reference characters designate corresponding parts, and in which:

Figure 1 is a side elevation; and, Fig. 2 is an inverted plan view.

Referring to the drawings, 1 designates a handle carrying a tang 2, having a projecting shoulder 3.

A body 4 is provided with a bifurcated end 5, disposed over the shoulder 3 and pivotally connected therewith by means of the pin 6, to permit the folding of the body 4 against the handle 1, the shoulder 3 being arranged in alinement with the handle 1.

The body 4 is provided with an offset

pointed end 7, adapted to be inserted in the head of the can and to form a fulcrum point. 40

Slidably disposed on the body 4 is a sleeve 8, adapted to be fixed on the body 4 at any desired point by means of the set-screw 9, and provided with a cutting blade 10 on its lower face. 45

One side of the handle 1 is provided with a pocket 11, adapted to receive the cutting blade 10 when the implement is folded.

Having thus fully described my invention, what I claim as new, and desire to secure by Letters Patent, is:—

1. A can opener comprising the combination of a handle, a tang carried by the handle and provided with a shoulder, a body provided with a bifurcated end disposed over the shoulder, a pin disposed through the bifurcated end of the body and the shoulder, and a cutting blade adjustably secured on the body. 55

2. A can opener comprising the combination of a handle provided with a pocket in one side, a tang carried by the handle, a body pivoted to the tang and provided with an offset pointed end, a sleeve adjustably disposed on the body and provided with a cutting blade, adapted to enter said pocket when the body is folded against the handle, and a set-screw carried by the sleeve adapted to lock the same on said body. 60 65

In witness whereof I have hereunto set my hand in the presence of two witnesses.

LOUIS PHILIPPE THERRIAULT.
